UNITED STATES PATENT OFFICE.

HENRY ACKERMAN, OF WEEHAWKEN, NEW JERSEY.

DESIGN FOR A BASE FOR GEM-SETTINGS.

42,428.

Specification for Design.

Patented Apr. 30, 1912.

Application filed December 2, 1911. Serial No. 663,616. Term of patent 14 years.

To all whom it may concern:

Be it known that I, HENRY ACKERMAN, a citizen of the United States, and a resident of Clifton Park, Weehawken, in the county of Hudson and State of New Jersey, have invented a new, original, and ornamental Design for a Base for Gem-Settings, of which the following is a specification, reference being had to the accompanying drawing, forming part thereof.

Figure 1 is a top plan of the base of the gem setting; and Fig. 2 is a side elevation

thereof, showing the manner in which the prongs or fingers which secure the gem to the base are attached to said base by means of lateral extensions from the inner ends of said prongs.

I claim:

The ornamental design for a base for a gem setting, as shown.

HENRY ACKERMAN.
